A pneumatic spring for use between the lateral frame members of the frame and bogie in a railroad car or a streetcar has a torus-shaped diaphragm having two co-planar ring-shaped beads the outer of which is sealingly secured to the frame and the inner of which is sealingly secured to a cap which is coupled to the bogie, preferably by way of a rubber spring. The coupling between the cap and the frame member of the bogie may comprise an antifriction bearing or a friction bearing to reduce the stressing and wear on the diaphragm. The interior of the diaphragm communicates with a plenum chamber in the frame member of the frame and the cap is provided with a projection which abuts against a partition in the frame forming the compartments of the plenum chambers in the event of a failure of the pneumatic spring.

FIG. 5

PNEUMATIC SPRING FOR RAILROAD CARS

BACKGROUND OF THE INVENTION

The present invention relates to improvements in pneumatic springs for use in railroad cars, streetcars or the like rail-mounted vehicles. More particularly, the invention relates to improvements in pneumatic springs which can be used between the wheel-mounted beam-free or cradle-free truck or bogie and the body and frame of a railroad car, streetcar, tramway or the like.

German printed publication No. 1,207,420 discloses a railroad car with two pneumatic springs interposed between the lateral frame members of the cradle-free bogie and the lateral frame members of the frame or body of the vehicle. Each spring comprises a torus-shaped diaphragm which resembles a ring-shaped trough having an open side facing the underside of the frame and bounded by two beads including an outer bead which is secured to the frame and an inner bead which is coupled to the truck. The two beads are normally located in two different horizontal planes, namely, the inner bead is disposed at a level below the outer bead. It was found that, when the vehicle travels in a sharp curve, the stressing of and the restoring forces acting upon the diaphragm are very pronounced. The resulting wear on the wheels can reach such proportions that it adversely affects the running of the vehicle along the rails. The substantial restoring is attributable to relatively high rigidity of the diaphragm, and such rigidity can also cause a slippage of and the resulting wear upon the beads especially that bead which is located at the lower level and is secured to a bearing ring on a pipe of the bogie in a manner not unlike the connection between an automobile wheel and a tubeless tire.

German Utility Model No. 7,018,231 discloses a modified pneumatic spring employing a diaphragm similar to that of the German printed publication No. 1,207,420 wherein the lower or inner bead of the diaphragm is secured to a rim provided on a tube which is mounted on the bogie. An anti-friction bearing is installed between the rim and the upper end of the tube. The rim has a cupped extension which is received in the tube and accommodates the component parts of an auxiliary or emergency stop which becomes operative in the event of failure of the pneumatic spring. The just described construction comprises a very large number of parts which contribute to the high initial cost of the pneumatic spring.

SUMMARY OF THE INVENTION

An object of the invention is to provide a novel and improved pneumatic spring which is simpler, lighter, more reliable, more rugged and less expensive than the aforescribed conventional springs.

Another object of the invention is to provide a pneumatic spring which improves the running characteristics of wheels on the bogie of a rail-mounted conveyance and contributes to longer useful life of the diaphragm.

A further object of the invention is to provide a novel and improved mounting for the torus-shaped diaphragm of a pneumatic spring between the bogie and the frame of a rail-mounted vehicle.

An additional object of the invention is to provide novel and improved connections between the beads of

the diaphragm and the frame and bogie of a streetcar or the like.

The invention is embodied in a vehicle, such as a railroad car or a streetcar, which comprises a wheel-mounted bogie or truck, a vehicle frame located above the bogie, and cushioning means including at least one pneumatic spring which is interposed between the frame and the bogie and comprises a torus-shaped hollow flexible diaphragm having an inner ring-shaped bead and an outer ring-shaped bead spacedly surrounding the inner bead and being normally at least substantially coplanar with the inner bead, connecting means sealingly securing the outer bead to the frame, a cap surrounded by and sealingly secured to the inner bead and having an arresting portion normally spaced from and located at the level below the adjacent portion of the frame, and coupling means securing the cap to the bogie. The frame has a plenum chamber in communication with the interior of the diaphragm, and the diaphragm has an open upper side extending between the two beads and facing the frame.

The novel features which are considered as characteristic of the invention are set forth in particular in the appended claims. The improved pneumatic spring itself however, both as to its construction and its mode of operation, together with additional features and advantages thereof, will be best understood upon perusal of the following detailed description of certain specific embodiments with reference to the accompanying drawing.

BRIEF DESCRIPTION OF THE DRAWING

FIG. 1 is a fragmentary vertical sectional view of a rail-mounted vehicle embodying a pneumatic spring which is constructed in accordance with a first embodiment of the invention and is shown in central vertical section;

FIG. 2 is a similar view of a portion of a vehicle embodying a modified pneumatic spring;

FIG. 3 is a similar view of a vehicle embodying a third pneumatic spring; and

FIG. 4 is a similar view of a vehicle embodying a fourth pneumatic spring and

FIG. 5 is a fragmentary side view of a railway vehicle having a wheel mounted track, a frame, and a pneumatic spring interposed between track and frame.

DESCRIPTION OF THE PREFERRED EMBODIMENTS

FIG. 5 partly illustrates a railway vehicle RV having wheel mounted trucks or bogies B, only one of which is shown, and a pneumatic spring 1, 8, which will be described later on in detail, between the truck B and the frame F of the vehicle.

Referring now to FIG. 1, there is shown a pneumatic spring which can be installed between a lateral frame member 4 of the body or frame F forming part of a railroad car or streetcar RV and a lateral frame member 11 of the bogie or truck B which is mounted on wheels, running along a pair of rails. The locations in which two pneumatic springs of the type shown in FIG. 1 can be mounted between the bogie B and the vehicle frame F are shown in FIGS. 1 and 2 of the aforescribed German printed publication No. 1,207,420.

The pneumatic spring of FIG. 1 comprises a torus-shaped hollow flexible diaphragm 1 having an outer ring-shaped bead 2 and an inner ring-shaped bead 3

which latter is surrounded by and is normally coplanar with the outer bead 2. The connecting device which sealingly secures the outer bead 2 to the frame member 4 comprises a clamping ring 5 and screws, bolts or analogous fasteners 5a. The inner bead 3 surrounds and is sealingly secured to a cap 6 which has a downwardly extending cylindrical portion 7 adjacent to the external surface of the diaphragm 1 immediately below the bead 3. The connection between the bead 3 and cap 6 is of the type similar to that between a tubeless tire and a rim on the wheel of an automotive vehicle. The cylindrical portion 7 of the cap 6 serves as means for properly centering the diaphragm 1 and for preventing inward bulging of the diaphragm in the region below the bead 3.

The upper side of the cap 6 is provided with a rib, rail or analogous arresting portion or projection 12 which serves as an auxiliary or emergency stop in the event of failure of the pneumatic spring and then abuts against an internal portion or portions 13 of the frame 4. Thus, if the diaphragm 1 is destroyed or punctured, the projection 12 abuts against the underside of the portion 13 and thereby prevents further descent of the respective side of the frame F toward the bogie B.

The partitions 13 is provided with one or more openings or ports 13a for the flow of a pressurized gaseous fluid which fills the interior of the diaphragm 1 and a plenum chamber 15 of the frame F. Since the upper side of the diaphragm 1 between the beads 2 and 3 is open, the interior of the diaphragm is free to communicate with all compartments of the plenum chamber 15, namely, with the compartments above and below the partition 13.

The coupling means between the frame member 11 of the bogie B and the cap 6 comprises a laminated elastomeric spring 8 consisting at least essentially of natural or synthetic rubber, a lower flange 8A which connects the lower end of the spring 8 to the frame member 11 by means of threaded fasteners 8B, and an upper flange 8D which connects the upper end of the spring 8 to the cap 6 by means of threaded fasteners 8E. Thus, the respective ends of the rubber spring 8 are rigidly connected with the cap 6 and with the frame member 11.

In the embodiment of FIG. 2, the cap 9 constitutes the upper race of an antifriction bearing 25 which forms part of the coupling means between the inner bead 3 of the diaphragm 1 and the frame member 11. The lower race 10 of the bearing 25 is secured to the flange 8D by the fasteners 8E. Rolling elements 9a are interposed between the races 9 and 10. Otherwise, the pneumatic spring of FIG. 2 is identical with the pneumatic spring of FIG. 1, i.e., the beads 2, 3 are normally located in a common horizontal plane and the two compartments of the plenum chamber 15 are free to communicate with each other and with the interior of the diaphragm 1.

In the embodiment of FIG. 3, the coupling means between the cap 6 and the frame member 11 of the bogie B comprises an antifriction bearing 26 having an upper race 27 which is rigid with the flange 8A, a lower race 14 which is bolted to the frame member 11, and rolling elements 28 interposed between the races 14, 27. Otherwise, the pneumatic spring of FIG. 3 is identical with the pneumatic spring of FIG. 1.

In the embodiment of FIG. 4, the cap 16 constitutes the outer sleeve of a friction bearing 29 which forms

part of the coupling means between the bead 3 and the frame member 11. The inner sleeve 17 of the friction bearing 29 is bolted to the flange 8D.

The purpose of the rubber springs 8 is to take up mainly vertical stresses. The manner in which the frame F is turnably connected with the bogie B is not shown in the drawing; such connection may comprise an anti-friction ball bearing mounted on the frame F and having a lower race cooperating with arms or levers provided on the bogie B. Reference may be had to FIG. 2 of the aforementioned German printed publication No. 1,207,420.

An important advantage of the constructions shown in FIGS. 2-4 is that the bearings in the coupling means between the inner bead 3 and the frame member 11 of the bogie B reduce the likelihood of subjecting the diaphragm 1 to excessive torsional stresses. This prolongs the useful life of the diaphragm. The rubber spring 8 reduces the likelihood of excessive stressing of the diaphragm 1 when the vehicle travels along a sharp curve and the distance between the lateral frame members 4 and 11 changes. Another advantage of the improved pneumatic spring is that it comprises a relatively small number of simple parts which can be readily assembled or taken apart. Since the diaphragm 1 is subjected to relatively small torsional stresses as a result of which its normal condition can be reestablished by resorting to relatively small restoring forces, the useful life of the diaphragm considerably exceeds the useful life of diaphragms in conventional pneumatic springs. Also, the wear on the wheels of the bogie B is less pronounced and the running of wheels on the rails is more satisfactory than in rail-mounted conveyances employing conventional pneumatic springs.

Without further analysis, the foregoing will so fully reveal the gist of the present invention that others can, by applying current knowledge, readily adapt it for various applications without omitting features which fairly constitute essential characteristics of the generic and specific aspects of our contribution to the art and, therefore, such adaptations should and are intended to be comprehended within the meaning and range of equivalence of the claims.

What is claimed as new and desired to be protected by Letters Patent is set forth in the appended claims:

1. A pneumatic spring arrangement comprising, in combination, plenum chamber means having an opening; pneumatic spring means including a torus-shaped hollow flexible diaphragm having an inner ring shaped bead and an outer ring shaped bead spacedly surrounding said inner ring shaped bead; connecting means sealingly securing said outer ring shaped bead to said plenum chamber means around said opening thereof; a cap surrounded by and sealingly secured to said inner ring shaped bead, said cap having a rigid projecting portion projecting toward a portion of said plenum chamber means located above said projecting portion, and coupling means adapted to secure said cap to a cushioned member, said plenum chamber means communicating through said opening with the interior of said torus-shaped hollow flexible diaphragm in which the air is pressurized in such a manner as to normally maintain said outer bead at least substantially coplanar with said inner bead and said projecting portion of said cap spaced from said portion of said plenum chamber means, said projecting portion however moving during

springing action through said opening at least partly into said plenum chamber means.

2. A combination as defined in claim 1, wherein said coupling means includes an antifriction bearing having an upper race constituting said cap, a lower race and rolling elements disposed between said races.

3. A combination as defined in claim 1, wherein said coupling means comprises a friction bearing having two coaxial sleeve-like portions one of which constitutes said cap and the other of which is rotatable relative to said one sleeve-like portion.

4. A combination as defined in claim 1, wherein said coupling means comprises a laminated rubber spring.

5. A combination as defined in claim 4, wherein said coupling means further comprises an antifriction bearing having a first race secured to said rubber spring, a second race, and rolling elements interposed between said races.

6. A combination as defined in claim 1, wherein said plenum chamber comprises several compartments and said frame is provided with at least one port establish-

ing a path for the flow of a pressurized fluid between said compartments.

7. A combination as defined in claim 1, wherein the common plane of said beads is normally a substantially horizontal plane.

8. A combination as defined in claim 1, wherein said cap comprises a cylindrical portion whose axis is substantially normal to the common plane of said beads and said diaphragm further comprises a substantially cylindrical portion immediately adjacent to said inner bead and surrounding said cylindrical portion of said cap in engagement therewith.

9. A combination as defined in claim 1, wherein said plenum chamber comprises a rigid partition extending transversely therethrough and substantially parallel to said inner bead, said partition dividing said chamber into two compartments, at least one port in said partition providing communication between said compartments, a portion of said partition forming said portion of said frame.
